United States Patent Office

Des. 178,313
Patented July 17, 1956

178,313

BIRD PERCH

Ludwig Stark, Springfield, N. J.

Application December 1, 1954, Serial No. 33,359

Term of patent 7 years

(Cl. D31—2)

Fig. 1.

Fig. 2.

Fig. 3.

Fig. 4.

Fig. 5.

Fig. 1 is a top plan view of a bird perch embodying my new design,

Fig. 2 is a side elevational view thereof,

Fig. 3 is a bottom plan view thereof,

Fig. 4 is a vertical sectional view thereof taken on line 4—4 of Fig. 3, and

Fig. 5 is a vertical sectional view thereof taken on line 5—5 of Fig. 3.

I claim:

The ornamental design for a bird perch, as shown.
